EDWARD CARL MUELLER, OF MILWAUKEE, WISCONSIN, ASSIGNOR TO STERLING WHEELBARROW COMPANY, OF WEST ALLIS, WISCONSIN, A CORPORATION OF WISCONSIN.

CLAMP FOR CONCRETE-FORMS.

1,115,719.

Specification of Letters Patent.

Patented Nov. 3, 1914.

Application filed November 21, 1913. Serial No. 802,270.

To all whom it may concern:

Be it known that I, EDWARD CARL MUELLER, a citizen of the United States, residing at Milwaukee, county of Milwaukee, and 5 State of Wisconsin, have invented new and useful Improvements in Clamps for Concrete-Forms, of which the following is a specification.

The object of my invention is to provide 10 a clamping device for holding the parts of concrete forms together while the material is hardening or setting, but the device may be used in other relations in which it may be found serviceable.

15 My device comprises a flexible band adapted to be placed about the form and readily bent into shape loosely conforming to the exterior shape of the form, a lever attached to one end of the band and provided with means for positively engaging 20 the band near its other end, and further means on the band for securing the lever in its tightening position on the form.

Prominent objects of my invention are to 25 provide efficient means for clamping the free end of the flexible band in the lever so there will be no slipping of the band through the lever as it is being swung into its tightening position, and to obviate sharp bends in 30 the flexible band thus increasing the ease with which it may be prepared for repeated use and increasing the life of the band when used repeatedly on the same size of form and consequently repeatedly bent and 35 straightened in very nearly the same place.

Other objects and advantages of my invention will be apparent from the following description taken in connection with the accompanying drawings, in which—

40 Figure 1—shows the clamp in longitudinal section as applied to a concrete form, only one corner of the form being shown. Fig. 2—shows a plan view of the clamping lever. Fig. 3—shows the end portion of the band, to which the lever is to be attached, having the securing device thereon, and Fig. 4—shows a perspective view of a wrench for 45 forcing the lever into tightening position.

Referring more in detail to the features 50 shown in the drawing, a concrete form is composed of planks as 10, extending longitudinally of the column or beam to be made, the planks which form one plane surface of the column or beam being attached to a 55 series of cleats as 11 in one instance shown

and 12 in the other instance. The abutting parts of the different sets of planks and cleats in the form are arranged to resist collapse of the form by external pressure.

In order to hold the different sides of the 60 form together tightly to prevent concrete leaking out while the forms are being filled, clamps are placed around them at frequent intervals of their length. This clamp consists primarily preferably of a piece of band 65 iron 13 of requisite strength, one end thereof being formed in a loop 14 in which the nose 15 of the lever 16 is loosely inclosed. The lever 16 comprises two parts, the handle or bar 17 and the jaw 18 pivotally connected 70 to the bar by the pin 19. Corresponding flat faces 20 and 21 are formed on the bar and jaw respectively, which faces extend parallel to each other and spaced apart a distance equal to the thickness of the band metal 75 when the lever is extended in straight line position as shown in full lines in Fig. 1, and are adapted to swing past each other in one direction to increase the size of the opening therebetween as shown in dotted lines in 80 Fig. 1. As shown in Fig. 1, these clamping faces 20 and 21 extend wholly on one side of the longitudinal center line of the bar 17 passing through the center of pivot pin 19, and the faces will therefore impinge on each 85 other when the handle 17 is swung in one direction relatively to the jaw 18, and will open or separate as the handle is swung in the opposite direction.

In operation, the band 13 is placed around 90 the form, the lever is held with the clamping faces open as shown in dotted lines; the free end of the band is passed between these faces and stretched conveniently tight by direct pull on the free end. The handle 17 95 is then swung toward the right, the first part of its movement serving to clamp the band 13 between the faces 20 and 21, the further movement of 17 in the same direction serving to pivot the lever as a whole 100 around the nose 15 and swing the clamp faces 20 and 21 with the band 13 clamped therebetween from the dotted to the full line position shown, thus stretching the band tightly around the form. If, on making a 105 part only of the swing to the right, the operator perceives that the band is not going to be sufficiently tight, he may swing the lever again to the left, thus opening the clamping faces and obtain a new and shorter 110

grip on the band. The part of the jaw 18 which the band 13 engages on the approach to the clamping faces is rounded as shown to avoid putting a sharp bend in the band when the clamp is set tight, as this bend must be at least approximately straightened before the clamp can be again used, and repeated sharp bends at or near the same place destroy the band.

10 A securing device consisting of a bar 22 having a series of apertures therein adapted to receive the end of the handle 17, is attached to the band 13 under the end of the lever as shown in Fig. 1. This bar 22 may 15 be pivoted to the band 13 by the clip 23 as shown or the band 13 may simply be passed through the first aperture and the bar 22 be positioned on the band 13 by hand.

In order to increase the leverage of 16, 20 lugs 24 are placed on either side of the handle adapted to be engaged by fingers 25 on the wrench 26 shown in Fig. 4 and in dotted lines in Fig. 1. An aperture 27 is provided in the wrench through which the bar 22 may 25 project, and a lug 28 is provided opposite the fingers 25 in order that the wrench may operate the lever in either direction.

While I have described my invention as embodied in the specific form shown in the drawing, it will be understood that I do not desire to limit myself to that form any closer than is pointed out in the claims as I contemplate many changes in details that will still fall within the limits specified in 35 the claims.

I claim,—

1. In a clamp for concrete forms, the combination of a flexible metallic band, a lever pivotally attached to one end of said band 40 and provided with means adapted to adjust-

ably hold the band near its free end, and a securing device for said lever consisting of an apertured bar pivotally engaging said band and adapted to swing over the free end of said lever and engage the same in an 45 aperture.

2. In a clamp for concrete forms, the combination of a flexible metallic band, a lever pivotally attached at one end to an end of said band, said lever comprising two parts 50 pivotally attached together, corresponding clamping faces one on each of said parts extending in a direction perpendicular to the longitudinal center plane of the lever passing through the center line of the pivot of 55 the lever and only on the side thereof toward the free end of the band, and a securing device pivoted to the band and arranged to engage the free end of said lever.

3. In a clamp for concrete forms, the combination of a flexible metallic band, a lever pivotally attached at one end to an end of said band, said lever comprising two parts 60 pivotally attached together, corresponding clamping faces one on each of said parts extending in a direction transverse to the longitudinal center plane of the lever passing through the center line of the pivot pin and only on the side thereof toward the free end 65 of the band, said clamping faces being substantially parallel when the lever is in extended straight line position, the surface of the pivoted jaw on which the band rests adjacent to the clamping face being curved through an arc of substantially ninety degrees. 70

EDWARD CARL MUELLER.
